(57) **CLAIM**

The ornamental design for a tool bit container, substantially as shown and described.

DESCRIPTION

FIG. 1 is a perspective view of a tool bit container in accordance with the present invention.

FIG. 2 is a rear perspective view of the tool container of FIG. 1.

FIG. 3 is a top plan view of the tool container of FIG. 1.

FIG. 4 is a front plan view of FIG. 1.

FIG. 5 is a rear plan view of FIG. 1.

FIG. 6 is a side plan view of FIG. 1.

FIG. 7 is the other side view of FIG. 1.

FIG. 8 is a bottom plan view of FIG. 1; and,

FIG. 9 is a perspective view in an open position of the tool container of FIG. 1.

The broken line portions of the disclosure are for illustrative purposes only and form no part of the claimed design.
